O. B. PECK, JR.

MAGNETIC SEPARATOR

Filed Oct. 3, 1923

UNITED STATES PATENT OFFICE.

ORRIN B. PECK, JR., OF LOS ANGELES, CALIFORNIA.

MAGNETIC SEPARATOR.

Application filed October 3, 1923. Serial No. 666,276.

To all whom it may concern:

Be it known that I, ORRIN B. PECK, Jr., of the city of Los Angeles, State of California, have invented certain new and useful Improvements in Magnetic Separators, of which the following is a specification.

My invention relates to separation, classification and concentration of mixed solids while in a sufficiently crushed state, the component parts of which are strongly magnetic and non-magnetic, or contain parts also which are relatively strongly and weakly magnetic, by subjecting such material to the force of magnetic attraction while in a suspended or depending position, under the influence of magnetic attraction, in a state of submergence in liquid, and at the same time to vibrations and washing energy of such liquid.

20 In the accompanying drawings, Fig. 1 is a top plan of my separator.

Fig. 2 is partly a side elevation and partly a vertical central section of the apparatus shown in Fig. 1.

25 Fig. 3 is a projected or straightened out illustration partly in elevation and partly in sections of certain parts of the apparatus, principally showing the relative position of the electromagnets and the tray, or liquid 30 and material container, to give a better understanding of their operating relations.

Fig. 4 is a detail of one of the magnets, with some of its associated parts, indicating the form of suspended accretion of material 35 when the magnet is located and connected in one way, and Fig. 5 is quite similar to Fig. 4, excepting that it illustrates two magnets located and connected so as to form a magnetic gap between the two, which will collect 40 the magnetic material in the form substantially as indicated.

As means for carrying my process of separation and classification, herein described, into effect, I provide a comparatively slowly 45 rotatable supporting member 2, which is mounted on a shaft 3, which shaft is both laterally journalled and stepped in a box 4, mounted on the bed plate 5 of the separator.

The upper part of this shaft is journalled 50 in a box 6, on the upper end portion of a bracket or stand 7, which is mounted at its base on the bed plate of the separator. The member 2, is secured to the shaft, as indicated, preferably through a hub 8, and on 55 the upper end of the shaft, as best illustrated in Fig. 2, is a worm wheel 9, engag-

ing a worm 10, which is carried on a shaft 11, journalled in boxes 12 and 13 respectively. On the outer end of this shaft is mounted a pulley 14, by which rotation may be 60 imparted to the shaft and its connected parts, from any appropriate source of power.

Suitably positioned on and carried by the member 2, are multiple electromagnets 15, 65 of structure and strength to serve the purposes required in operation of the separator. These magnets are illustrated as having enlarged magnetic heads or poles 16, positioned so that their several lower surfaces 70 will be in substantially a uniform transverse plane, adapted to uniformly approach and be carried by their supporting element 2, in close proximity to the upper surface of a liquid containing receptacle 17. 75

This container or receptacle is preferably circular to conform to the circular assemblage of the magnets, as indicated in Fig. 1, and is preferably of non-magnetic material, positioned so that the upper surface of its 80 top wall or cover 18 may be located closely to the lower surface of the several magnets, as illustrated, and permit such magnets to be carried around in close proximity to the same. 85

This upper wall, which is especially indicated by the numeral 18, is preferably constructed with zones or portions of different thicknesses, as best illustrated in Fig. 3. One part thereof, which is the initial or feed 90 zone in operation, is comparatively thin, to enable the material introduced into the tray to approach very closely to the magnets, and farther around in the course of travel of the magnets there is a portion of this wall, 95 which I have indicated as 18', appreciably thickened, in order to deflect the material being operated on, a greater distance from the magnets, which will result in the intensity of attraction on such material at this 100 part, being lessened, from the fact that, as is well known, the intensity or effective force of an electromagnet, lessens with increased distance between the substances operated on and the magnet. 105

Still further around in the course of movement of the magnets, the wall is again increased in thickness, which portion is indicated by 18², and here the effective strength of attraction on the material will 110 be further lessened, for the same reason stated above, and still further along, as in-

dicated by 18^a, the thickness of this wall is further pronouncedly increased, in order to deflect the material then remaining, out of the highly effective zone of the magnets and 5 enable it to be easily removed by means of a liquid jet under-pressure, supplied by a pipe 19. The bottom part of the container is at this point depressed sufficiently to afford desired room for insertion of the 10 pipe, 19, and its proper operation.

The container is flexibly supported in position by means of suitable members 20, in a manner to enable it to be quite rapidly vibrated by any desired means, as by a shaft 15 21, having a crank formed on its end, which connects to the container by a suitable connecting rod or part 22; through an appropriate fastening 23. This shaft may be rotated by a pulley, 24, mounted on its 20 outer end, the shaft being journalled in a box 25, to rotatably hold it in position.

The supporting frame of the separator may be of any form desired, but, in addition to the bed plate 5; and supporting 25 bracket 7, I have shown connecting or supporting parts 28.

To serve in partly dividing the internal part of the container into zones or compartments with respect to the different 30 thicknesses of its upper wall 18, I have provided partial partitions 26, as indicated in Fig. 3, and to serve as discharge or drainage means for material and liquid from the container, there are provided hollow short 35 pipes or nipples 27.

In the operation of my separator, the magnet-supporting member 2, is revolved at a comparatively slow speed through the mechanism described for that purpose, and 40 material for separation is introduced into the container through a feed pipe 29, connecting with any suitable source of supply, in quantities sufficient to maintain the chamber in the container full of the material and liquid. The mixture should contain a sufficient proportion of liquid to 45 enable it to flow very freely.

As soon as the material enters the container in close proximity to the magnets, 50 the magnets, of course, having been properly energized for effective operation, the magnetic constituents of such mixture will be at once attracted and held in a suspended position in the liquid, against the 55 under-side of the upper wall 18 of the container, while the non-magnetic material will settle or seek the bottom of the container, or partly remain in disconnected suspension in the liquid.

60 As the magnetic constituents are collected in the manner just stated, they will carry with them in entanglement, more or less non-magnetic particles, but during the operation, the container is quite rapidly vibrated through revolution of the pulley 24

and its connected part, producing a washing and vibrating action of the liquid, which in effect will wash and shake out the entangled non-magnetic particles, and further, in the revolution of the magnets, this collection or accretion will be tumbled, scoured and carried along around the course of movement of the magnets in an agitated state on the underside of the wall 18, giving further opportunity for washing and 75 eliminating the non-magnetic particles which will fall in this, being in the first part of the container with relation to its operation.

As the magnets revolve, moving with 80 them the magnetic accretion along on the under side of the wall 18, this material will be progressively brought within the zone of greater thickness 18' of the wall, thereby being deflected a greater distance 85 from the magnets, and consequently the strength of magnetic attraction operating on the same will be lessened, and then, under the washing and vibrating influence, the constituents being so moved, which are of weakest magnetic intensity, will be washed, shaken and separated from those more strongly magnetic, and be collected in this 90 part of the container, and moreover, in the further rotation of the magnets, the constituents remaining on the under-side of the wall will be moved to the zone 18^a of still greater thickness, and into a weaker influence of magnetic attraction and here, those then relatively magnetically weaker will in 95 like manner be detached and separated and then collected in that portion of the container, while those most strongly magnetic still remaining sufficiently under the influence of the magnets, will be moved further 100 around in the container to the thickest portion 18^b of the wall, where they will in such movement be deflected far enough away from the magnets to enable the accretion to be easily washed off by the impact 110 of liquid from the pipe 19, employed for that purpose.

It will therefore be seen that in this performance there will first be separated the non-magnetic constituents, then those relatively weaker magnetically, then those relatively of medium magnetic susceptibility, leaving those most highly magnetic, all of which constituents or products may be drawn or flow from the container through 115 their respective discharge passages therefrom.

The magnets may be relatively positioned and connected in a manner as to produce independent or individual effects in the accretion of the magnetic constituents in operation, as indicated in Fig. 4, or in manner as to form effective magnetic gaps as indicated in Fig. 5, where the accretion of material to a large extent forms over the 120 125 130

gaps so produced. This may be determined as desired, governed more or less by the character of material being operated on.

It will of course be understood that the energizing current to the magnets shall be proper and sufficient for the uses intended and that the rapidity or violence of vibration and washing effect of the liquid in the container shall be such as to suitably 10 cooperate with the effective strength of the magnets and the material under treatment.

What I regard as new and desire to secure by Letters Patent is:

1. In a magnetic separator the combination of a supporting member, adapted to be rotated in a horizontal plane, an electro-magnet thereon adapted to be carried by said member, a vibratable liquid and material container located below said magnets 15 with its top side below and adjacent to the path of travel of the magnet, means for revolving the supporting member and means for vibrating the container, substantially as described.

2. In a magnetic separator a supporting

member adapted to be rotated in a substantially horizontal plane, an electro-magnet thereon adapted to be carried by said member, a vibratable liquid container located in proximity to said supporting member 30 with one side adjacent to the path of travel of the magnet, having zones of increased thickness, means for revolving the supporting member and means for vibrating the container, substantially as described. 35

3. In a magnetic separator a rotatable supporting member, multiple electro-magnets mounted thereon, having the lower surfaces of their poles on a substantially uniform plane and adapted to be carried in a circle by said supporting member, a liquid and material container located in proximity to said pole surfaces, having a wall with successive areas of increased thickness in the path of travel of 40 said magnet, means for rotating the supporting member and means for vibrating the container, substantially as described. 45

ORRIN B. PECK, JR.
